TOP SHELL FOR AN EXPANSIBLE BRACELET

Edward L. Gay, Jr., Edgewood, and Wilfred H. Gay,
Woonsocket, R. I.

Application July 13, 1955, Serial No. 36,953

Term of patent 3½ years

(Cl. D45—4)

Fig. 1.

Fig. 2.

Fig. 3.

Fig. 4.

Fig. 1 is a top plan view of a top shell for an expandable bracelet showing our new design;

Fig. 2 is a side elevational view thereof;

Fig. 3 is a sectional view thereof taken along line 3—3 of Fig. 1; and

Fig. 4 is a sectional view thereof taken along line 4—4 of Fig. 1.

We claim:

The ornamental design for a top shell for an expandable bracelet, substantially as shown.
